LABORATORY MIXER

Robert Stannis Quandt, Deerfield, Ill., assignor to Sybron Corporation, Rochester, N.Y.

Filed Mar. 26, 1973, Ser. No. 344,916

Term of patent 7 years

Int. Cl. D24—02

U.S. Cl. D32—2

FIG. 1

FIG. 2

FIG. 3

FIG. 4

FIG. 1 is a top plan view of a laboratory mixer showing my new design;

FIG. 2 is a front elevation view thereof;

FIG. 3 is a left side elevation view thereof; and

FIG. 4 is a right side elevation thereof.

I claim:

The ornamental design for a laboratory mixer, substantially as shown and described.
